UNITED STATES PATENT OFFICE.

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS.

PLATING MECHANISM FOR STRAIGHT-KNITTING MACHINES.

Application filed August 20, 1918. Serial No. 250,675.

To all whom it may concern:

Be it known that I, WILLIAM S. PARKER, a citizen of the United States, residing at Rockford, in the county of Winnebago and 5 State of Illinois, have invented certain new and useful Improvements in Plating Mechanism for Straight-Knitting Machines, of which the following is a specification.

This invention relates in general to 10 straight knitting machines, and has more particular reference to plating mechanism therefor. I have illustrated my improvements in connection with a straight knitting machine of the Burson type, the general principles and operation of which are 15 disclosed in the Burson Patent No. 616,600 granted Dec. 27, 1898. While it was possible with a machine of this character to knit fabrics of innumerable shapes and with 20 various yarns so as to produce plain, fancy and irregular designs, determined by the pattern cylinders, the machine lacked facilities for performing the operation known as 25 plating. In this art, plating means knitting the face of a fabric with one kind of yarn and the back with another; and the present invention contemplates knitting of this 30 character by means of straight knitting machines, especially of the type mentioned, as will appear more fully hereinafter.

The primary object, therefore, of this invention is to provide novel plating mechanism for straight knitting machines, enabling plating to be performed throughout 35 various knitting operations of which such a machine is capable.

With this general object in view it is necessary that the plating and facing yarns shall be so controlled that either one or the 40 other will be fed to the needles first according to the changes from continual round to course knitting, from light to heavy 45 yarns, and from one color to another, etc., as may be required by the character and design of the work; and another object of the invention is to provide a simple and practical mechanism for controlling the yarn changes so that regardless of the variations 50 and changes in the design, the plating and facing yarns will always be properly fed to the needles.

Another object of the invention is to control certain changes of the plating and facing yarns from a pattern cylinder or 55 drum, whereby the ends desired are attained

in a most simple, direct and advantageous manner.

These and other objects and attendant advantages will be appreciated by those skilled in the art as the invention becomes better 60 understood by reference to the following description when considered in connection with the accompanying drawings, in which—

Fig. 1 is a fragmentary plan view of a 65 straight knitting machine embodying my improvements;

Fig. 2, a cross-sectional view through the machine taken substantially on the line 2—2 of Fig. 1, on a reduced scale; 70

Fig. 3, an end view of those parts of the machine shown in Fig. 1, looking forwardly from the back end;

Fig. 4, a view illustrating one example of 75 a stocking knit by this machine;

Fig. 5, a diagrammatic illustration of the 80 yarn changes;

Fig. 6, a plan view of a yarn-carrier, approximately full size, and noted hereinafter as the No. 1 yarn-carrier;

Fig. 7, a similar view but showing the 85 yarn distributor reversed;

Figs. 8 and 9, side and end views respectively of the yarn-carrier shown in Fig. 6; and

Fig. 10, a cross-sectional view through the 90 yarn-carrier taken substantially on the line 11—11 of Fig. 6, but illustrating the construction of the No. 2 yarn-carrier, simply by the omission of one part which will be 95 mentioned hereinafter.

Since the general construction and operation of the Burson straight knitting machine shown in the drawings is well understood by those familiar with the art and is described in various patents, I have deemed it necessary to illustrate and describe only such parts of a machine as will enable a clear understanding of my present invention to be had. The well known parts include the 100 parallel needle beds 12 and 13, needles 14, presser hooks 15, cam slides 16 and 17 for advancing and retracting the needles and presser hooks respectively, base bars 18, hook caps or yarn carrier guides 19, jack 105 levers 21 and pattern cylinders 22 and 23 mounted on the shafts 24 and 25 respectively. Other well known parts are the transfer wheel, designated in general by character 26 adapted to remove a yarn-car- 110

rier from operative position and substitute another therefor, and the drive bars 27 adapted to be reciprocated from a cross head, not shown, for moving through the agency 5 of a drive hook 28, a yarn-carrier back and forth across the needle beds. Viewing Fig. 1, the front side of the machine is at the lower side of the sheet and the front end, at the right hand end of the sheet. The mechanism for operating the pattern cylinders, 10 the yarn-carrier drive bars and the transfer wheel in proper timed relation is not shown, since such mechanism is well known in the art. Consequently, as will appear 15 hereinafter, when mention is made of any of these mechanisms being operated in certain predetermined relation it will be understood that they are so governed by proper control mechanism. Before entering into a 20 consideration of my improvements, *per se*, it might be well to state in a general way the operation of the parts thus far mentioned.

The pattern cylinders govern the needles 25 so as to bring a greater or less number into action for determining the shape of the knitting. The cam slides 16 and 17 are reciprocated by the same cross head that reciprocates the yarn-carriers and thereby 30 projects and retracts the needles and presser hooks in timed relation with feeding of yarn to the needles. In a machine of this character the yarn drawn by the carrier from an overhead delivery, not shown, is carried in 35 back and forward strokes across the needle beds by the yarn-carrier and fed to whatever needles are projected or brought into action by the needle operating mechanism. In this way, the knitting may be performed 40 in continual rounds or courses; that is, in the back stroke away from the transfer device the knitting may be with one bank of needles and upon the forward or return stroke the needles of the opposite bank will 45 be brought into action, thus completing a round of knitting. When the knitting is not in rounds it is considered as knitting in courses; for example, the knitting may be back on one bank of needles in one course 50 and forward on the same bank of needles in another course. Thus, a fabric, such as a stocking, might be knit by rounds and courses, employing either one or more yarn-carriers for knitting different portions of a 55 stocking with yarns of different color or character. In knitting a split foot stocking, that is, one in which the yarn for the sole is different from that for the ankle and front of the foot, the knitting for this portion of the 60 stocking is in courses, producing a union or suture extending from the finish of the toe to a point in the ankle. In other words, a split foot stocking has a sole knit of a reinforced or relatively heavier yarn than that 65 employed in knitting the front of the foot

and the leg or major body portion. Generally, this heavier yarn is employed for knitting the toe portion, and the sole and heel up to and including the high splice at the commencement of the ankle portion. It 70 is to this style of stocking that my improvements have special reference, since the knitting of a split foot stocking involves knitting in both rounds and courses and consequently requires various changes of yarn-carriers 75 and of the different yarns employed in plating as will be described presently.

Referring now to Fig. 4, it will be noticed that the split foot stocking illustrated herein is knitted of two yarns, viz: a relatively 80 heavy yarn indicated by the section lines and a lighter yarn noted by the non-sectioned portion. For this purpose two yarn-carriers are employed; one for the heavy yarn and the other for the relatively lighter yarn. 85 Following this example, the yarn-carrier having the heavier yarn may be called the No. 1 yarn-carrier and that for the lighter yarn may be termed the No. 2 yarn-carrier. The No. 1 yarn-carrier knits the toe portion from A to B in continuous rounds, 90 whereupon the No. 2 yarn-carrier knits courses back and forth on one bank of needles and the No. 1 yarn-carrier knits similar courses back and forth on the opposite bank of needles, this operation being 95 carried on alternately, producing the split foot portion from B to C, with the exception of the heel pocket D—E, which is knit separately by the No. 1 yarn-carrier during 100 which period the No. 2 yarn-carrier is inactive as is well understood in this art. This produces a union or suture on each side of the foot from the finish of the toe portion to the finish of the high splice. The 105 ankle and major leg portion of the stocking are knit as shown with the No. 2 yarn-carrier and the upper leg portion from F to G is knit with the No. 1 yarn carrier. This particular stocking, it will be understood, is 110 simply taken as an example for illustrating the method of plating with my improvements, which are to be presently described, and it will be borne in mind that the particular design and shape of the knitted fabric 115 might be varied to produce any effect desired, including the use of two or more yarns differing in color, quality, character and 120 plating.

With regard to my improvements, the 120 plating is performed by simultaneously delivering two yarns from a yarn-carrier to the needles through separate distributing eyes, so that one yarn will be fed to the needles in front of the other, thus positively 125 insuring that a given yarn will be knit on the face and another on the back of the stocking. I have, therefore, termed the yarn on the face of the knitted fabric the "fac- 130 ing yarn," and that yarn on the back the

"plating yarn." In a straight knitting machine of the character referred to herein, the plating yarn must be fed to the needles first, that is, just in advance of the facing 5 yarn, so that when both yarns are knit simultaneously the facing yarn will be on the face, and the plating yarn on the back of the fabric. In practice, any of various combinations of yarns might be employed to 10 produce the desired effects; for example, the facing yarn might be wool and the plating yarn cotton, or the facing yarn silk or fibre silk and the plating yarn cotton, or the facing and plating yarns may be of different 15 color, qualities and plies. Thus, it is evident that a large variety of designs and effects might be produced and especially so, with the provision for plating by means of a simple control mechanism which will enable 20 the plating to be automatically performed through either continual round or coarse knitting.

The yarn-carriers mentioned are preferably both of the same construction, with one 25 exception which will be presently noted. Referring to Figs. 6 to 11 inclusive, each yarn-carrier comprises a body 29 having slides 31 adapted to fit in the ways 32 of the yarn-carrier guides 19 and having an upper 30 turned end 33 adapted to be operated by the drive-bar hook 28. Mounted upon the yarn-carrier are the usual latch openers 34 and the presser feet 35. Instead of a single distributing eye for the yarn, the carrier is 35 equipped with means for distributing in a predetermined manner a plurality of yarns so that one of the yarns will be positively fed to the needles before the other. In the present instance, this yarn distributing 40 means consists of a yarn tube 30 revolvably mounted on the spaced upper and lower cross plates 36 and 37 of the yarn-carrier and formed with two yarn passages 38 and 39 on diagrammatically opposite sides of 45 the pivot axis of the yarn tube. This yarn tube is normally held with its passages 38 and 39 in transverse alignment with respect to the needle beds. As a consequence, one of the yarns will be fed to the needles just in 50 advance of the other yarn. When the front bank of needles is in operation and the yarn-carrier as shown in Fig. 6 is moved in its back stroke, that is, away from the transfer wheel, the plating yarn will be fed to each 55 needle first, that is, just in advance of the facing yarn, the latter being knit on the face of the fabric. At the end of the back stroke the yarn tube will be revolved a half revolution so that during the forward or return 60 stroke when the needles of the opposite row are in action the plating yarn will similarly be the first to enter the needles. This produces a continuous round of knitting in which the facing yarn is positively knit on 65 the face of the fabric. For revolving the

yarn tube in these half revolution movements, I have provided what might be termed a switch, which upon being actuated by any one of various controlling elements disposed in its path as the carrier is reciprocated, will be moved from one position to another for correspondingly reversing the position of the yarn distributing eyes. This switch consists of a part 41 pivotally mounted on a post 42 intermediate the plates 36 and 37 and shaped to provide a segmental gear 43 in mesh with a pinion 44 fixed with the yarn tube 30. The pivoted part 41 is also provided with a radially and upwardly extending arm 45 which is adapted to be 70 actuated for oscillating the part 41 and, consequently, revolving the yarn tube in half revolution movements. The arm 45 as shown in Figs. 6 to 9 inclusive, is provided with an upstanding finger 40 adapted to be 75 actuated by means independent of those which operate directly upon the arm, as will appear hereinafter. The only difference between the No. 1 and No. 2 yarn-carriers is the fact that the No. 2 carrier does not include this upstanding finger 40. On the No. 2 yarn-carrier the arm 45 appears as shown in Fig. 11. Stops 46 and 47 fixed on the carrier are provided for limiting oscillation of the part 41 so that when the latter is oscillated from one position to another, the yarn tube will be revolved simply through a half revolution. Thus, when the part 41 is moved from the position shown in Fig. 6 to that shown in Fig. 7, the distributing eyes 100 38 and 39 will be moved in a counter-clockwise direction through 180°, and upon returning the part 41 to its original position the distributing eyes will be moved in the reverse direction the same distance. In 105 order to hold the yarn tube and its operating part in set position and to assist in moving the parts from one position to another as will be presently seen, a spring 48 is provided. This spring connected at one end to the post 49 and at its opposite end at 51 to the part 41 diametrically opposite from the arm, is arranged so that when the point 51 passes the centerline between the pivot axes of the part 41 and the yarn tube 30, the 110 spring will move the part 41 into contact with either stop 46 or 47, depending as is evident, on which side of said centerline the connection 51 is disposed. Thus, it will be seen that the spring 48 holds the parts 30 and 41 in the positions shown in both Figs. 6 and 7, and that upon moving the arm 45 in a clockwise direction (viewing Fig. 6) just past the centerline mentioned, the spring 115 will complete the movement, carrying the 120 arm against the stop 47. By reason of this construction, the position of the yarn distributing eyes may be reversed almost instantly, since in addition to the quick action of the spring, the switch is operated by being 125 130

brought into contact with controller elements upon reciprocation of the yarn-carrier.

Control mechanism is provided for actuating the yarn changing switches of the yarn-carriers at different points in their operation, it being necessary that the yarn changes be made almost instantaneously in order not to interfere with the continuity of the knitting operation. In order to obtain in a most simple and practical manner, the various yarn changes required for knitting a split foot stocking of the character described above, or of any design requiring both course and round knitting where many changes occur, I have provided a control mechanism which is operated in part from a pattern cylinder and from the transfer wheel. The controller elements by which the position of the yarn is changed on the carrier by actuation of the arm 45, consist in the present instance, (referring to Figs. 1 and 3) of a front stop 52 positioned on one arm of the transfer wheel in the path of the arm 45, a back stop 53 movable into and out of the path of the arm 45 by the pattern mechanism and an intermediate spring member 54 likewise movable into and out of the path of the arm 45 by the pattern cylinder. The front stop 52, shown best in Figs. 1 and 3, is simply a set screw on one arm of the transfer wheel 26 in the path of the arm 45 of the No. 1 yarn-carrier and so arranged that when said yarn-carrier is moved into the guideways of the transfer wheel at the completion of the forward stroke the arm 45 will, if it is in the position engaging the stop 52 as shown in Fig. 7, be thrown to the opposite stop so as to reverse the position of the yarns as mentioned above. The switch of the No. 2 yarn-carrier held in the next adjacent guideways of the transfer wheel, as shown in Fig. 3, will likewise be operated by a front stop 55 when positioned upon the transfer wheel. Of course, if the arm 45 of either switch is in the position shown in Fig. 6 when its carrier is entered upon the transfer wheel no change in the position of the yarn occurs. It follows, therefore, that each time either yarn-carrier leaves the transfer wheel its arm 45 will be in the position indicated in Figs. 1 and 6. The controller element 53 in the form of a plate or arm adapted to be positioned in the path of the arm 45 of a yarn switch at the end of the back stroke, is carried by a lever adapted to be operated by one of the pattern cylinders. This lever, best shown in Fig. 2 and indicated in general by reference character 56, is of a built-up construction including a drum engaging foot 57 pivotally mounted at 58 and having laterally spaced followers 59 and 61 adapted to ride respectively on the peripheries of separate pattern disks fixed to the cylinder 22 des-

ignated generally by 62 and 63. The lever includes also an upstanding portion 64 carrying a fixed inwardly extending arm 65 which terminates in the controller element or stop 53. A spring 66 connected to the part 64 of the lever simply serves to hold the latter in contact with the pattern disks so as to take up any slack. The disks 62 and 63 are shaped to raise and lower the stop 53 at predetermined intervals. Thus, when through rotary movement of the pattern cylinder 22 in a counter-clockwise direction the points 67 and 68 reach the followers 59 and 61 respectively, the latter will be operated to raise the stop 53, in which position this stop will be held, due to the continuity in the periphery of the cylinder disks, until the points 69 and 71 are reached, which latter cause the stop to be lowered again to operative position. The lever 56 and its cylinder pattern are also utilized for operating the intermediate controller element 54, which, shown best in Fig. 1, is in the form of a flat spring fixed to a rock shaft 72 mounted in bearings 73 on one of the base bars 18. The rock shaft is provided with an outwardly extending crank arm 74 disposed beneath the portion 65 of the lever 56 and held in co-operative relation therewith by a flat spring 75 carried by said lever. Referring now to Fig. 3, it will be noted that the spring member 54 and the crank arm 74, both fixed to the rock shaft 72, are so relatively arranged that when the stop 53 is in operative position, the member 54 is in an inoperative position, that is, withdrawn from the path of the yarn-changing switches. When now the lever 56 is operated by the pattern cylinder to raise the stop 53 in the manner just mentioned, the crank 74 will be rocked upwardly by said lever, thereby swinging the spring controller 54 downwardly and into the path of the upstanding finger 40 of the No. 1 yarn-carrier. It will be here noted that the purpose of the controller element 54 is solely to actuate the finger 40 of the No. 1 yarn carrier and that this controller element even though in operative position, will not actuate the yarn changing switch of the No. 2 yarn-carrier, because the switch operating arm 45' of the latter passes idly beneath the controller element 54. From the foregoing, it will be plainly evident that when the controller element 53 is lowered into operative position the intermediate controller element 54 is simultaneously raised to inoperative position, and vice versa, although the controller element 53 actuates the yarn switches of both yarn-carriers when in operative position, whereas the controller element 54 operates only the yarn switch of the No. 1 yarn-carrier, the movements of the controller elements being controlled from a common source on a pattern cylinder.

Having now in mind the construction of my improved plating mechanism, reference may be had to Figs. 4 and 5, in following a description of the general operation of the machine with respect to the plating. As already mentioned, I have taken as an example best illustrative of my improvements, the knitting of a split foot stocking of the design indicated in Fig. 4. In knitting this stocking a heavier yarn is employed for knitting the toe, sole and heel than for knitting the upper foot, ankle and leg of the stocking. At the same time all of the knitting is plated so that throughout any portion of the stocking the yarn on face is different from that on the back of the fabric. The machine as shown in Figs. 1, 2 and 3 with regard to the plating mechanism, is in a position commencing to knit, it being observed that the No. 1 yarn-carrier is in position to commence the first back stroke and that the controller element 53 is in lowered operative position. The No. 1 yarn-carrier carries the relatively heavy yarn with the facing and plating yarns through the distributing eyes 38 and 39, respectively. The toe portion A to B, Fig. 4, is knit round and round entirely by the No. 1 yarn-carrier. While knitting the toe, the needles in the front bank of the machine are in operation during the back stroke and upon the return or forward stroke the knitting is by needles on the opposite bank. The diagrammatic illustrations in Fig. 5 are laid out corresponding with the arrangement of the needles, yarn-carriers and yarn switches, as shown in Fig. 1. That is, the horizontal column (a) Fig. 5, represents at the right the No. 1 yarn-carrier at the commencement of the back stroke, showing the facing yarn 38 and plating yarn 39, the former of which will be knit on the outside or face of the fabric by needles in the front row or bank as the carrier moves to the left in the back stroke. At the completion of said back stroke the switch 45 will be reversed by the controller element 53 as indicated in the diagram, thus reversing the position of the facing and plating yarns so that they will be knit respectively on the face and back of the fabric by the opposite needles when the round is completed on the return or forward stroke. At the completion of the forward stroke the yarn switch 45 is reversed by the controller element 52. It is thus seen that while knitting the toe, the yarn switch is reversed at the end of each stroke by the controller elements 53 and 52 respectively, the knitting being in continuous rounds. At the finish of the toe, the transfer wheel will be revolved in a clockwise direction, viewing Fig. 3, to place the No. 2 yarn-carrier in operative position. At the same time, the pattern cylinder will raise the controller element 53 to inoperative position and lower the controller

element 54 into operative position. However, it will be noted that this latter controller element 54 will have no effect on the yarn switch of the No. 2 carrier, as mentioned above. The relatively lighter facing and plating yarns of the No. 2 yarn-carrier will be fed to the front bank of needles in the back stroke and also on the forward stroke without change in position. This operation is illustrated in the horizontal column (b) Fig. 5, in which it will be seen that the facing yarn 38' and the plating yarn 39' remain unchanged and are simply knit back and forth on the front bank of needles with the facing yarn on the face of the fabric during both strokes. At the finish of this course the transfer wheel will be turned in a counter-clockwise direction, viewing Fig. 3, to place the No. 1 yarn-carrier again in operative position. This yarn-carrier will then knit a back and forward course on the opposite bank of needles with the facing yarn outermost so that this yarn will be knit on the face of the fabric. During the back stroke, viewing the horizontal column (c) Fig. 5, the position of the yarns must be reversed before the yarns reach the needles in order that the plating yarn will be fed first to the needles which are in action at the backside of the machine. Since the controller elements remain in the same position, the switch 54 will actuate the pin 40 on this yarn switch, thereby reversing the position of the facing and plating yarns before the yarn-carrier reaches the needles. The plating yarn 38 will be fed first to this bank of needles during both the back and forward strokes, the position of the yarn switch being reversed at the completion of the forward stroke by the controller element 52 on the transfer wheel. This knitting of courses by the No. 2 and No. 1 yarn-carriers will be continued alternately from the finish of the toe B until the finish of the high splice C at a point in the ankle, with the exception of the heel pocket which will be mentioned presently. During this knitting, the controller elements remain stationary as indicated in the columns (b)—(c) Fig. 5, that is, with the element 53 raised and the element 54 lowered. This produces what is commonly known as a split foot stocking having a union or suture at each side of the foot from the finish of the toe H to the finish of the high splice I. The heel pocket D—E is knit by the No. 1 yarn-carrier alone, during which period the No. 2 carrier is obviously inactive, as is well understood in this art. The ankle and leg portions of the stocking may be knit in any manner desired, and in the present instance, the ankle and leg portions from C to F are knit with the No. 2 yarn-carrier in continual rounds with the controller element 53 in operative position as indicated in the horizontal (d) Fig. 5, so

- that the position of the yarns will be reversed at the end of each back and forward stroke. If desired, the No. 1 yarn-carrier may be thrown into operation to knit the 5 upper leg portion F—G. This completes the knitting of the stocking in which the entire fabric is automatically plated irrespective of the number of yarn changes and changes from round to course knitting.
- 10 It is believed that the foregoing conveys a clear understanding of the operation and principles of my invention and of the objects prefaced above; and it should be understood that while I have illustrated and described 15 but one working example of my improvements various changes and modifications might be made in the construction and arrangement without departing from the spirit and scope of the invention as expressed 20 in the appended claims, in which—
- I claim:
1. Plating mechanism for knitting machines of the straight type, comprising in combination with the needles, a yarn-carrier, 25 a transfer mechanism, a yarn tube on the yarn-carrier for separately guiding a plating yarn and a facing yarn, a switch on the yarn-carrier for reversing the position of the yarns, means on the transfer mechanism for 30 actuating the switch so that the latter with its yarn-carrier will always leave the transfer mechanism in the same position, and a controller movable into and out of the path of the switch for actuating the same during 35 reciprocation of the yarn-carrier.
  2. In a knitting machine, a plurality of reciprocable yarn-carriers, each constructed for carrying a plating and a facing yarn the position of which may be reversed, a 40 transfer mechanism for the yarn-carriers having means for causing the relative position of the yarns of each yarn-carrier to be the same when it leaves the transfer mechanism, and controlling means for causing at 45 predetermined intervals in the operation of said yarn-carriers, the position of the yarns to be reversed.
  3. In a knitting machine, a plurality of reciprocating yarn-carriers, each constructed 50 for carrying a plating and a facing yarn the position of which may be reversed, a controller for reversing the position of the yarns of a yarn-carrier substantially at the end of its back stroke, and a second controller adapted at predetermined intervals 55 to reverse the position of the yarns of a yarn-carrier at a point intermediate the ends of its stroke.
  4. In a knitting machine, a first and a second 60 yarn-carrier each constructed for carrying a plating and a facing yarn, the position of which is adapted to be reversed, transfer mechanism for controlling the period of operation of the several yarn-carriers, a pattern cylinder, a controller element operated 65 by the pattern cylinder and adapted for causing the position of the yarn of said yarn-carriers to be reversed at predetermined intervals, and a second controller element operated by the first controller element 70 for reversing the position of the yarn of one of the yarn-carriers at predetermined times.
  5. In a knitting machine, the first and a second reciprocable yarn-carrier, each constructed for carrying a plating and a facing 75 yarn the position of which is adapted to be reversed, transfer mechanism for controlling the periods of operation of the several yarn-carriers, and controllers for governing the position of the yarns of the several yarn-carriers in the following sequence: reversal of the yarn at opposite ends of the stroke of the first yarn-carrier during continual round knitting of the toe portion of a stocking; non-reversal of the yarn of the first and second 80 yarn-carriers during the alternate courses of the same while knitting the split foot portion of a stocking, and reversal of the yarn of the second carrier at the opposite end of its strokes while knitting continual 85 rounds of the leg of a stocking.
  6. In a straight knitting machine, the combination with opposed banks of needles, of a plurality of yarn-carriers each having a pair of reversible distributing eyes 90 for a plating and a facing yarn and each adapted for independent operation during which both yarns are fed to the needles, pattern mechanism for controlling the needles and yarn-carriers to produce a split foot 95 stocking, and controllers for automatically reversing the distributing eyes of said yarn-carriers to cause the facing yarns to be knitted on the face of the fabric during the different cycles of the yarn-carriers. 100
  7. In a straight knitting machine, the combination with opposed banks of needles, of a plurality of yarn-carriers each having a pair of reversible distributing eyes 105 for a plating and a facing yarn and each adapted for independent operation during which both yarns are fed to the needles, pattern mechanism for controlling the needles and yarn-carriers to produce a special fabric requiring knitting in courses employing both banks of needles and in courses employing one of either bank of needles, and automatically operated controllers for reversing the distributing eyes of the yarn-carriers. 110
  8. In a straight knitting machine, the combination with opposed banks of needles, of a plurality of yarn-carriers each having a pair of reversible distributing eyes 115 for a plating and a facing yarn and each adapted for independent operation during which both yarns are fed to the needles, pattern mechanism for controlling the needles and yarn-carriers to produce a special fabric requiring operation of one yarn-carrier 120

through a different cycle from that of another, and controllers for automatically reversing the eyes of said yarn-carriers in conformance with the different cycles of said 5 yarn-carriers.

9. In a straight knitting machine, the combination with opposed banks of needles, of a first and a second yarn-carrier, each having a pair of reversible distributing 10 eyes for a plating and a facing yarn and each adapted for independent operation during which both yarns are fed to the needles, a switch on each yarn-carrier for reversing its distributing eyes, pattern mechanism for controlling the needles and yarn-carriers to produce a 15 split foot stocking, and means for automatically reversing the distributing eyes of said first and second yarn-carriers during the respective cycles thereof to effect plating of said split foot stocking.

10. In a straight knitting machine, the combination with opposed banks of needles, of a plurality of yarn-carriers each having a pair of reversible distributing eyes for a plating and a facing yarn and each 20 adapted for independent operation during which both yarns are fed to the needles, a switch on each yarn-carrier for reversing the position of the distributing eyes, and means for automatically operating said 25 switches, one in a cycle of operation different from the other.

11. In a straight knitting machine, the combination with opposed banks of needles, of a plurality of yarn-carriers each having a pair of reversible distributing eyes 35 for a plating and a facing yarn and each adapted for independent operation during which both yarns are fed to the needles, a switch on each yarn-carrier for reversing its distributing eyes, pattern mechanism for 40 controlling the operation of the needles and yarn-carriers, and automatically operated controllers movable into and out of position for operating said switches for controlling the position of the plating and facing 45 yarns in conformance with the pattern of the fabric.

12. In a straight knitting machine, the combination with opposed banks of needles, of a plurality of reciprocable yarn-carriers, means on each yarn-carrier for carrying a plating and a facing yarn, and for reversing the position thereof so that either yarn may be fed first to the needles, mechanism for controlling the period of operation 50 of said yarn-carriers, and mechanism for causing the plating and facing yarns of one yarn-carrier to be presented to the needles in different order from the presentation of the plating and facing yarns of the other 55 yarn carrier.
